DISPENSING MECHANISM

Rudolph G. Birr, Lombard, Ill., assignor, by mesne assignments, to American Linen Supply Co., Carson City, Nev., a corporation of Nevada

Application January 17, 1947, Serial No. 722,590

12 Claims. (Cl. 242—55.5)

1

This invention relates to improvements in dispensing apparatus, and one of its phases is particularly directed to the proper dispensing of sheet material from a supply-roll. Another phase is directed to improvements in stop mechanisms, and time-stop mechanisms, applicable to any type of dispensing apparatus. Another phase of the invention relates to a time-stop controlled automatic-feed mechanism, useful in paper dispensing devices of the tear-off type, in which the paper is dispensed by pull on the paper, and in which after tear off no paper is made visible or accessible until the end of a time period, at the end of which period a portion of the paper is automatically moved to visible and accessible position so it may be pulled to obtain a full length allowed, before the time-stop is again set.

Problems relating to the art of constructing paper dispensing mechanisms have always been to obtain a compact and relatively cheap mechanism, operable by a pull on the paper without tearing the paper, and therefore operable by minimum application of power. Every change of one structure generally requires a corresponding change in another. The dispensing of paper from a supply-roll involves special problems which are again related to the character, placement, strength and arrangement of springs, and methods of assembly of the stop mechanism or of the time-stop mechanism.

A discussion of problems in this art, may be helpful to an understanding of this invention. One of the problems in dispensing sheet material from a supply roll by means of feed rolls which control and are controlled by a stop mechanism, has been to avoid jamming and/or uneven feeding of the material. In order to reduce frictional drag of the mechanism the supply-roll has been mounted on a spindle for free rotation, but when so mounted over-spinning often occurs when, during feeding the feed rolls are suddenly stopped as a result of engagement of the stop mechanism to limit the length or amount of the material which can be withdrawn at a single dispensing operation. To properly feed a sheet of material which has opposite parallel sides, it should always be fed so that a line perpendicular to those sides is parallel with the axes of the feed rolls. In prior devices, when surplus material accumulates at a point between the supply roll and the meeting line of the feeding rolls, jamming or feeding askew often occurs.

Heretofore when this spinning occurred a surplus amount of the material left the supply roll,

2

and often became jammed by being so disposed as to enter between the feed rolls. When this happened there were formed between the rolls a plurality of layers of the material instead of the single layer. As a result of this multiple layer condition, the material became so jammed as to make it necessary for a service man to open the cabinet, remove the jammed material from the feed rolls, and then re-thread the material between the feed rolls. Jamming wastes the material, and increases the cost of servicing, to say nothing of rendering the device inoperative sometimes over long periods before servicing can be attended to.

15 The present invention reduces spinning and overcomes jamming and yet permits sufficiently free rotation of the supply roll by providing means for supporting the supply-roll in such manner and in such relation to the feed rolls that over-spinning is reduced, yet when supply-roll spinning does occur, the surplus reeled-off material cannot enter between the feed rolls.

Another problem in this art relates to reduction of the amount of force necessary to be applied by a pull on the paper, to rotate the feed rolls and to set the stop mechanism, and to condition certain power-supplying springs for subsequent action to release the stop mechanism and move it and a timer mechanism to release position. In some cases a spring is used to obtain automatic feed-out of the paper following release of the stop. The real problem then is in all cases to reduce friction to a minimum and to so construct and arrange those parts which are controlled by springs that the weakest possible spring or springs may be used.

25 In dispensing devices of the class herein, springs are used for releasing the stop mechanisms and for moving the stops (and also a timer mechanism therefor when used) to fully retracted or release position. The stop mechanism is controlled by and controls a dispensing roll or rolls. One of the dispensing rolls is generally called the measuring roll and against this 30 measuring roll a presser roll acts, and the rolls are driven by the paper when pulled. Therefore, in addition to overcoming the action of the stop-retracting spring during dispensing, there is considerable friction in the mechanism itself also 35 to be overcome.

40 The power for operating the stop mechanism to set the stop or to set the time-stop mechanism is applied by the user, through paper to the measuring roll, by a pull on the paper. The 45 amount of power which can be thus applied is

quite limited by the relatively cheap and fragile quality of the paper and also by the fact that the paper is often pulled by a single wet hand or by two wet hands.

It has always heretofore been a problem to construct and arrange the parts of the mechanism and to select springs of proper power so as to avoid breakage of the pulled paper and yet use a spring having power adequate to properly retract the stop, as well as a timer therefor when used.

The problem has been rendered more difficult in cabinets of the type herein in which a short length of paper is automatically moved by additional spring means to a position accessible to the user, on release of the stop mechanism, or of a time-stop mechanism. Since the power of this operation is also supplied by a spring, there are thus two springs used in this automatic feed-out type of cabinet. It is, therefore, against the action of various frictions and of both springs that the pulled paper must act.

Various arrangements of the parts and positions and qualities of springs have been used in an effort to obtain proper power action without tearing of the paper, during a dispensing operation. The present invention so arranges the stop surfaces of the stops in relation to the timer mechanism and the means for operating it by the stop, as to align the elements so that power can be applied most advantageously and effectively for obtaining release of the stop mechanism.

Another problem has been to obtain a smooth acting timer slide, and to avoid the use of that slide as one of the stops of a stop mechanism. Heretofore it has been the practice to use a part of a reciprocal timer slide as a stop, and such a practice is shown in Grunwald Patent No. 2,298,882. It has also been the prior practice to use a leverlike stop which in turn operated a sliding element of a timer. Such a scheme is shown in Birr Patent No. 2,193,759. Both of these schemes have objections. In the first mentioned scheme the slide and its guides are submitted to violent impacts when one stop engages the slide. This action is detrimental to the timer slide. On the other hand the timer shown in Birr requires the timer slide to be passed through a slot in a plate which supports the mechanism and requires the slide to extend in a direction which is parallel with the rotative axis of the measuring roll. This scheme is objectionable because of the tendency of the slide to tip and bind in the slot. This binding tendency was overcome in the Grunwald patent, but in that patent the slide was used as a stop, with the objection previously noted.

The present construction provides a timer mechanism in which the timer slide is not submitted to stop impacts, and in which the slide does not pass through a slot in one of two plates, on which all of the mechanism is supported.

Objects of the invention therefore are: To prevent jamming of the paper; to provide a new means for supporting and centering the supply roll against axial motion; to provide means to reduce over-spin of the supply roll; to provide a mechanism by which surplus paper resulting from spinning of the supply roll is formed into a loop so it can not be jammed into the feed rolls; to provide a form of stop mechanism in which stop release is facilitated, to the end that the power spring for obtaining stop release can be of minimum size, whereby the less strain is put on

the paper during pulling for dispensing and there is less likelihood of breaking of the paper due to excessive strain required for pulling out; to provide a new structure and arrangement of the stops, and of the stopping surfaces of the stops, and of the pivotal relation of the stops to one another; to provide an improved mechanism for automatically feeding the paper after stop release, and generally to provide a compact arrangement of all the parts, yet providing a cabinet in which a supply roll of maximum capacity can be received.

Features, objects and advantages of the invention will be pointed out in the description of the drawings, and in said drawings:

Figure 1 is an elevation of the inner unit, showing the time-stop mechanism with the stop engaged, as during the timing period, and with the cover of the cabinet in section;

Figure 2 is an elevation from the opposite side of the inner unit, showing the automatic feed-out device positioned in correspondence to the position of the parts in Figure 1;

Figure 3 is a front elevation of the inner unit with the cover in section;

Figure 4 is a vertical section taken approximately on a line 4—4 of Figure 3, illustrating the anti-jamming loop-forming structure and action;

Figure 5 is a top plan, with the cover in section;

Figure 6 is a detail section on line 6—6 of Figure 1, showing how the second or hook-stop is pivotally mounted, and also showing how the centering disks of the supply-roll supporting roller are rotatably mounted on the trunnions of said roller;

Figure 7 is a detail section on line 7—7 of Figure 1, showing how the timer and stop operating links are arranged and pivoted.

Figure 8 is a detail section on line 8—8 of Figure 1, showing the construction of the upper guide of the timer slide;

Figure 9 is a detail section on line 9—9 of Figure 1, showing how the pawl for preventing reverse motion of the measuring roll is mounted; and

Figure 10 is a detail section on line 10—10 of Figure 2, showing how the link for the automatic feed-out spring is attached to the finger-operable feed-out disk.

The cabinet comprises an inner wall section and outer cover section. The inner section comprises a rear wall 1 having an arcuate forwardly projecting upper marginal flange 2 having a centrally located depending keeper. Attached to this rear element 1 are two upright plates 3, connected by out-turned vertical flanges 4 with the back 1, as by welding. Each plate 3 has an out-turned bottom flange 5. An each plate also has a top out-turned flange 6 from the rear of which extends an upturned flange 7 which is secured to the rear plate 1, as by welding. On these plates 3 is mounted the entire dispensing mechanism.

The cover 11 is pivoted at 12 to upstanding marginal flanges 8 bent from the flanges 5. The cover can swing to a position below the inner section. The bottom of the cabinet is formed by plate 15 which is attached to the bottoms of flanges 5, as by welding. This plate 15 has at its forward margin an upstanding flange 16, provided with fingers 17 which lie in grooves 18 of a measuring roll 19, which roll has trunnions 20 and 21 suitably held in bearings provided in the plates 3.

In Figure 4 there is illustrated an important phase of this invention relating to means for preventing jamming of the paper by the feed rolls following overspinning of the supply-roll due to the sudden engagement of a stop mechanism, during dispensing.

Arranged above and yieldably urged against, the measuring roll 19 is a presser roll 25 having trunnions 26 journaled in bearing openings 21 in the plates 3. Swingable about trunnions 26 is an apron having the form of a plate 28 the function of which is to separate the paper 13 from a knife 14 at the bottom of the cover. After the paper has been torn off by the knife, the apron presses the paper against the forward surface of the measuring roll. This apron 28 is swingingly hung by ears 29 through which the trunnions 26 pass. Suitable springs 30 arranged on the outside of the plates 3, are suitably connected with the trunnions 26 to force the presser roll 25 against the measuring roll 19.

Arranged rearwardly of the presser roll 25 and above and partly over the measuring roll is a roller 31 journaled by means of trunnions 32 in the plates 3. The position of this roller in relation to the feeding rolls is important. In this instance the roller 31 is of slightly less diameter than the presser roll 25. However its uppermost surface is at a slightly higher level than that of the upper surface of the presser roll 25, as indicated by the line B—B.

The supply-roll is indicated at 35 and is held on a spindle 36 having trunnions 37 which are guided in slots 9 of the plates 3. These elements constitute means so mounting the supply-roll that it can rotate on and move toward the roller 31 as supply-roll diameter decreases. When the paper is being fed or is being pulled out by the user, that portion 40 of the paper which lies between the roller 31 and the meeting line of the feed rolls 19 and 25 forms a straight line. However when the stop mechanism (later to be described) engages, the supply-roll having been given a momentum due to dispensing action, generally continues to spin or to rotate, and surplus paper accumulates. By the use of this invention this surplus paper is made to form a loop 41, the lower portion of which lies partly against the presser roll and over said roll, and another portion of which lies under and against the supply-roll. This loop is directed forwardly and upwardly over the presser roll 25. As shown by dot and dash lines at 42 this loop may be of varying lengths but in no case is there any movement of the surplus paper downwardly toward the meeting line of the feed rolls.

Disks 33, one rotatable on each of the trunnions 32 are interposed between the ends of the roller 31 and the plates 3. The inner surfaces 34 of these disks are conical and these conical surfaces converge inwardly and are opposed to one another, and together act as automatic rotatable means adapted to locate or center the supply roll in relation to the feed rolls and to maintain that centering during dispensing, that is prevent axial motion of the supply-roll after centering. By having the elements 33 capable of rotating with the roller 31 or independently thereof slippage can occur either between the roller 31 and the supply-roll or between the disks 33 and the supply roll.

Since the diameter of the roller 31 is very substantially less than that of a full supply-roll, its rate of rotation as frictionally driven by the supply-roll will be much greater than that of the rotative rate of the supply-roll, whereby some

frictional resistance to supply-roll rotation is obtained during dispensing. This resistance reduces overspinning and is a valuable feature per se as well as in combination with a loop forming function of the roller 31 as related to the feeding roll.

The expression "free loop" as used herein means, the formation of surplus paper in any manner which will prevent its accidental entry between the feed rolls. Insofar as I am aware this function of preventing jamming has never before been successfully accomplished. It is to be noted that over-rotation of the supply roll in feed out direction forms a loop which always rises over the presser roll and is in fact guided upwardly by said roll, since this roll remains stationary from the moment that the stop engages and the material is pinched and held at the meeting line of the rolls. That part of the surplus material nearest the presser roll may be said to climb over that roll, being urged to do so by the feeding action of the over-lying, overspinning feed roll.

It is to be noted that, the larger the supply roll the greater is the spin which occurs when the stop-mechanism suddenly engages. It is desirable to use as large a supply roll of material as possible so that the cabinet will not have to be serviced so frequently, and the present cabinet provides for the use of a supply-roll of maximum diameter. Of course, when this large roll is first introduced into the cabinet, it will be given more powerful and prolonged momentum, when the stop engages, so that a larger loop may be formed while the diameter of the supply roll remains large. However, as the diameter of the supply roll decreases the formed loop may be smaller. It is also possible to take up the loop already formed if, following an unusually violent operation of the stop-mechanism, some subsequent operations are performed very much less violently.

The stop mechanism now to be described is representative of one of many stop mechanisms which can be used in relation to the loop-forming phase of this invention. Nevertheless this stop mechanism is in itself unique and presents structural advantages which it is believed are heretofore unknown to this art.

The time-stop mechanism has been shown in the position which best illustrates that part of this invention concerned with the alignment of the various elements including stopping surfaces on a mid-line A—A extending in direction of reciprocation of the timer slide. This alignment and arrangement of the parts facilitates stop release as well as reduces to a minimum those frictional and spring resistances which must be overcome by a pull on the paper, during dispensing.

Fixed to the trunnion 20 of the measuring roll 19, and spaced outwardly from plate 3 is a first stop 43, having an arcuate stopping surface 44 engageable with a corresponding surface 45 which is on a hook-like extension 46 of a second lever stop 47, pivoted as at 48 to the plate 3. This screw 48 passes through an outwardly punched out spacer portion of the plate 3, see Figure 6. By this means the hook 46 is brought into the plane of rotation of the stop surface 44. This surface 44 has its center of curvature in the axis of the pivot 48, and the stop surface 45 has its center of curvature in substantially the same axis. The second stop 47 is provided with an arcuate slot having its center of curvature in the axis

of pivot 48, and through this slot loosely extends the trunnion 32 of the roller 31. A spring 49 is attached, as shown to the short arm of the lever-like second stop and acts to move the stop in counter-clockwise direction to release it.

The stop surface 45 of the second stop is brought into the path of the corresponding surface of the first stop by means of a link 50 which has therein a keyhole slot 51. Through this slot passes a headed pin 52 which is threaded into the first stop 43 and the head of this pin is of greater diameter than the width of the slot but is of less diameter than the upper circular portion 53 of the slot whereby assembly is simplified. The link is pivoted to the second stop by a pivot 54 which also forms the pivot for a short link 55, in turn pivoted on a projection 56 of a slide plate 57 having a guide opening 58. The surface of the slide 57 is in flat engagement with the outer surface of plate 3, but, due to the cut-outs in the plate, the area of its frictional engagement with the plate 3 is not great. A guide 59 in the form of a bracket is arranged in the guide opening 58 and is suitably secured by fastening devices 60 to plate 3. This guide has a shelf 61 which carries a vacuum cup structure including a cup 62 that lies above the shelf and a tubular element 63 which passes through and is secured to the shelf, and rotatively-adjustable means 64 below the shelf for regulating the entry of air through the tube to annul the vacuum in a manner well known to this art. The slide 57 is provided with a horizontal projection 65 to which is attached a second cup 66 cooperative with the first cup for vacuum attachment when the slide 57 is moved downwardly by means of its link connection with the second stop, as this stop 47 is moved downwardly by means of the link 50 and the pin previously described. The slide is also guided by a pin 67 passing through a slot 68 of the slide, see also Fig. 8.

The bottom surface of the guide opening 58 of the slide 57 is adapted to engage the bottom surface of the guide bracket 59 to limit upward movement of the slide and the second stop, as urged by the spring 49. The degree of upward motion of the slide is such as to assure that the bottom of the hook 46 will rise out of the rotative path of the first stop 47. Other means may be provided for limiting this movement of the stop and slide.

It will be noted that the cups, and the guides for the slide and the pivots of 54, 56 and stopping surfaces 44 and 45 are so related as to be substantially aligned on mid line A—A when the stop surfaces are engaged. This line extends in direction of reciprocation of the slide, and therefore release of the stop surfaces is facilitated and the application of power by a relatively weak spring to retract the slide is rendered more effective. It is further noted that the stopping surface 44 faces forwardly or outwardly, and that the long arm of the second stop which has the hook, lies under the bottom of the slide 57 and over the first stop; a compact arrangement.

When the parts are positioned as shown in Figure 1 the vacuum action of the timer cups prevents release of the stops, and when the second stop is released, automatic feeding occurs by means herebelow described. Only a sufficient amount of automatic feeding occurs to project the paper to a position accessible and visible to the user, so that he may thereafter pull out additional paper. This automatic feeding force is provided by the mechanism shown in Figure

2 and the position of this mechanism corresponds to that of the position of the mechanism of Figure 1.

A finger disk 70 is attached to the trunnion 21 of the measuring roll and this disk lies as shown in Figure 3 between the outer side of one of the plates 3 and vertical wall of the cover 11. The disk has fingers 72 which project through a slot 71 in the front wall of the cover, see Figure 5. This disk is used for turning the feed rolls preliminarily during servicing of the cabinet, to obtain engagement of the paper between the feed rolls. The disk 70 has a pin 73, and connected with this pin is a rod 74 having (see Figure 10) a hook 75 engaging a groove 76 of a sleeve 77 on the pin 73. The opposite end of the rod 74 is connected by spring 78 with a hooked projection 79 of the flange 6.

After the vacuum of the timer cups has been annulled to allow upward movement of the slide and release of the stops by means of the spring 49, the spring 75 acts to move the disk in this instance through an angle of about 90 degrees to the position shown by the dot and dash line 25 C. This action moves the paper 13 from its position in Figure 4 to a visible position below the knife 14, at which it is accessible for grasping and pulling.

As the above automatic feed-out action occurs 30 after release of the timer, the first stop will move from the position shown in Figure 1 also through an arc of about 90 degrees. Thereafter when the user pulls on the paper, the first stop continues its rotation in clockwise direction, to again assume the position shown in Figure 1, the pin 52 having during this movement engaged the bottom of the slot 51 and moved the second stop into the path of the first stop so that the parts again finally assume the positions of Figure 1.

Retrograde movement of the measuring roll 19 is prevented by a ratchet disk 80 fixed to the trunnion 20 at a point between the end of the measuring roll and the inner side of one of the plates 3. A pawl 81 pivoted at 82 (see Figure 9) to the plate 3, acts by gravity to engage teeth of the disk, some of these teeth being shown in dotted lines in Figure 1.

The timer vacuum cups hold the second stop against the action of its spring, and in this instance against upward motion, during which said stop rotates in anti-clockwise direction. At the end of the timing period the cups are automatically released and the second stop 47 moves upwardly, and as soon as it moves out of the path of the stopping surface of the first stop 44 the spring 75 automatically moves the measuring roll in feed-out direction. The upward movement of the pivoted stop to release position is permitted by the slotted link arrangement, the slot 51 of the link merely riding upwardly on the pin 53 of the first stop. When the measuring roll is automatically moved the pin 53 swings the link 50 toward the right in the figure, and the pin rides downwardly in the slot. When the user pulls on the paper the pin 53 engages the lower end of the slot and as rotation of the measuring roll continues (due to pull on the paper) the mechanism is again brought finally to the positions shown in Figures 1 and 2.

The cover 11 is provided with a locking mechanism, generally designated by numeral 90 said mechanism having a hook 92 which engages a keeper 91 attached to flange 2 of the back 1, in the manner best shown in Figure 2. Any suitable type of lock may be used. It is to be noted

that the cover is so pivoted that it may be swung downwardly to a position below the inner section, and in such position that if desired a supply-roll may be supported within it preparatory to servicing the cabinet.

What I claim is:

1. A dispensing device having feeding rolls and a stop mechanism which abruptly stops the dispensing action of said rolls, a roller, a supply-roll resting on the roller, and means so supporting the supply-roll that it can freely rotate on and move toward the roller as supply-roll diameter decreases, said feeding rolls and said roller and supply-roll being so related that when a loop of surplus material is formed as the supply-roll overspins due to abrupt stopping of the feed rolls by the stop mechanism said loop will not enter between the feeding rolls.

2. A device for dispensing sheet material from a supply roll having, upper and lower feed rolls which are adapted either to be moved by the material or to move the material, a time-stop mechanism and connecting means by which the same controls and is controlled by said feed rolls, means for automatically and rapidly moving said rolls in feeding direction on release of the time-stop mechanism, a supply roll, and a roller for supporting the supply roll at its bottom for free rotation and in such relation to the feed rolls that when a loop of surplus material is formed as the supply roll overspins as a result of sudden stopping of said feed rolls either by said stop mechanism when the rolls are being moved by the material or as a result of sudden stopping of the feed rolls at the end of their rapid automatic feeding motion said loop of surplus supply material will be formed in such manner that it cannot enter between the feed rolls.

3. A device for dispensing sheet material from a supply-roll comprising, a pair of plates, feed rolls journaled in and between the plates, a roller having trunnions journaled in the plates and adapted to support the supply-roll while the material is being dispensed from it through the feed rolls, and disks rotatable on said trunnions and adapted to automatically center the supply roll and to prevent its axial motion on said roller.

4. A device for dispensing sheet material from a supply-roll comprising, a pair of plates, feed rolls journaled in and between the plates, a roller having trunnions journaled in the plates and adapted to support the supply-roll while the material is being dispensed from it through the feed rolls, disks rotatable on said trunnions between the ends of the roller and said plates and adapted to automatically center the supply roll and to prevent its axial motion on said roller, and a secondary support for the supply roll adapted to move toward the roller and about which the supply roll can rotate.

5. A dispensing device having, a measuring roll having a first stop having a stop surface, a reciprocal slide, guides for the slide aligned on a midline of the slide which extends in direction of its reciprocation, a second stop having a stop surface engageable with the stop surface of the first stop, means pivoting the second stop, a link and first and second pivots connecting it respectively to said slide and said second stop, means pivoted on said second pivot and operable by means on the first stop to move the stop surface of the second stop into the path of the stop surface of the first stop during ro-

tation of the roll, timer means on the slide and on one of the guides of the slide aligned on said midline and adapted to be engaged and to hold the pivoted stop in stop position for a time period, a spring acting to move the second stop and said slide from stopping position, said first and second pivots and stop surfaces being so related as to be substantially aligned on said midline when said stop surfaces are engaged, whereby release of the stop surfaces is facilitated and the application of power by said spring to retract said slide is rendered more effective.

6. A dispensing device having a measuring roll, having a first stop, directly connected thereto, a reciprocal slide, guides for the slide aligned on a midline of the slide which extends in direction of its reciprocation, a pivoted second stop engageable with the first stop, a link and first and second pivots connecting it respectively to said slide and said second stop, means pivoted on the second pivot and operable by means on the first stop to move the second stop into the path of the first stop during rotation of the measuring roll, timer means on the slide and on one of the guides of the slide adapted to be engaged to prevent release of the stops until the end of a time period, a spring acting on the second stop to move it and said slide from stopping position, said guides and first and second pivots and the stopping surfaces of said stops being so related as to be substantially aligned on said midline when said stops are engaged, whereby release of the stops is facilitated and the application of power by said second stop to retract said slide is rendered more effective.

7. A paper dispensing device having, a measuring roll which is moved by a pull on the paper, a stop connected to the measuring roll and having a stopping shoulder facing outwardly, a second stop and means pivoting it to swing into the path of the first stop, said second stop having a stopping shoulder which faces inwardly, a timer including a slide having a part engageable with another stationary part for securing the slide in a given position until the end of a time period, a link and pivots connecting it respectively to the slide and to the second stop in a manner to move the stop into stopping relation with the first stop during timer-setting action, means for applying power to move said second stop from stopping position when said slide is released by said timer, the said link pivots and engaged stopping shoulders being disposed to be on a line which extends in direction of reciprocation of the slide, and means operable by said first stop for forcibly moving the second stop into the path of the first stop and then releasing the second stop for movement away from stopping position when the timer elements separate.

8. A dispensing device having upright plates, a measuring roll journaled in said plates and having a first stop directly connected thereto, a reciprocal slide comprising a plate flatly slidable against one flat face of one of said upright plates, guides for the slide, aligned on a mid-line of the slide which extends in direction of its reciprocation, a pivoted second stop engageable with the first stop, a link and first and second pivots connecting it respectively to said slide and to said second stop, means pivoted on the second pivot and operable by means on the first stop to move the second stop into the path of the first stop during rotation of the measuring roll, timer means on the slide and on one

of the guides of the slide adapted to be engaged to prevent release of the stops until the end of a time period, and a spring acting on the second stop to move it and the slide from stopping position, said guides and first and second pivots and the stopping surfaces of said stops being so related as to be substantially aligned on said mid-line when said stops are engaged, whereby release of stops is facilitated and application of power by said second stop to retract said slide is rendered more effective.

9. In a cabinet for dispensing sheet material in roll form, a first measuring roll and a stop mechanism therefor, a second roll for holding the material in measuring relation to the measuring roll, a roller adapted to support a supply roll for free rotation, means for maintaining the supply roll in proper relation to the roller as the diameter of the supply roll decreases, said second roll and roller both being disposed over the measuring roll, the roller being so disposed that the supply roll material leads from it forwardly and downwardly toward the meeting line of the first and second rolls, said second roll being so disposed that when the supply roll is supported on the roller the second roll is spaced downwardly from the periphery of the supply roll, whereby when the supply roll overspins as a result of sudden stopping of the measuring roll by its stop mechanism a loop of surplus material is formed over the second roll and between it and said supply roll.

10. A dispensing cabinet for sheet material in roll form which comprises a pair of feed rolls one of which is controlled by a stop mechanism, a roller which is adapted to be engaged by the lower periphery of a supply roll to allow free rotation of the supply roll and means for maintaining a supply roll and roller relation such that the supply roll can move downwardly as its diameter decreases, said feed rolls and roller being so arranged that when spinning of the supply roll occurs after the stop mechanism engages, a loop of roll-feed material will be formed which points away from the meeting line of the feed rolls.

11. A dispensing cabinet for sheet material in roll form having a measuring roll controlled by a stop mechanism to limit the amount of material dispensed, a pinch roll adapted to hold the material in measuring relation with the measuring roll, a roller arranged rearwardly of

the pinch roll and upon which the bottom of the supply roll rests, and the top surface of which roller is disposed substantially in the same horizontal plane as the top of the pinch roll, and a shaft adapted to pass through the supply roll axially and means guiding it at both ends to move downwardly toward the roller, and the pinch roll being so positioned as to be spaced from the periphery of the supply roll as supported by the roller.

10 12. A device for dispensing sheet material from a supply-roll comprising, feed rolls, and automatic means for suddenly rapidly rotating the rolls, a roller on which a supply roll is adapted to rest while the material is being dispensed from it by the feed rolls, said roller being adapted to be rotated by frictional action of the supply-roll, a secondary support for the supply roll adapted to move toward the roller and about which the supply-roll can rotate, the diameter of the roller in relation to the initial diameter of the supply-roll being so small that the rate of rotation of the roller is very much greater than the rate of rotation of the supply-roll, 20 whereby some frictional resistance to supply-roll rotation is obtained during dispensing to reduce over-spinning of the supply-roll.
